Assistant Examiner — Emily Anna Saunders

(57) **CLAIM**

The ornamental design for a game controller fidget toy, as shown and described.

DESCRIPTION

FIG. 1 is a front perspective view of the game controller fidget toy, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a bottom, rear and left side perspective view thereof.

The broken lines in the drawings are for the purpose of illustrating portions of the game controller fidget toy and form no part of the claimed design.

1 Claim, 8 Drawing Sheets
